AUTOMATIC FEEDING APPARATUS FOR
STEAM BOILERSJames F. Gilmore, Kalispell, Mont., assignor of
one-half to Valjean Riley, Kalispell, Mont.

Application October 13, 1941, Serial No. 414,890

6 Claims. (Cl. 122—456)

This invention relates to water feeding apparatus for a steam boiler, and its general object is to provide an apparatus which is fully automatic to maintain a normal water level within the boiler.

A further object is to provide a water feeding apparatus for a steam boiler, that is controlled solely by the quantity of water within the boiler, that is when the water level therein drops below normal, a float actuated switch controlled by the water within the boiler, opens a circuit to a second switch, the latter being actuated to closed position by a float in the water feeding means, and the second switch opens and closes the circuit to a motor, for the latter to not only open and close valves which control the passage of water from the feeding means to the boiler, but the motor also opens the second switch so that water is fed at intervals to the boiler, until the level therein becomes normal, thence the first switch closes to render the apparatus inactive.

A further object is to provide a water feeding apparatus, that is simple in construction, inexpensive to manufacture, easy to install and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a diagrammatic view of the apparatus, with the circuit open and the parts in a position, just after the water level in the boiler has become normal, and the receiving tank is being filled from the supply tank, so as to render the apparatus ready for the next boiler filling operation.

Figure 2 is a detail view illustrating the float and motor operated switch for controlling the motor, in closed position, and the motor operated tripping lever in a position just prior to opening the switch.

Figure 3 is a view similar to Figure 2, with the parts in a position just after the switch has been opened by the tripping lever.

Referring to the drawing in detail, the reference numeral 1 indicates a steam boiler, 2 a supply tank and 3 a water receiving and steam pressure tank, the tank 3 being suitably supported above the boiler, and the tank 2 above

the tank 3, as shown, so that the water will flow by gravity from the tank 2 into the tank 3 and from the latter into the boiler. For that purpose, a pipe line 4 is provided between the tanks and a pipe line 5 is provided between the tank 3 and the boiler, the pipe lines having check valves 6 and 7 respectively therein, to prevent return of water to the tanks, as will be apparent. The pipe line 5 has its lower end terminating slightly above the bottom of the boiler, and the upper end of the pipe line 5 connects with the tank adjacent its bottom. The lower end of the pipe line 4 connects with the pipe line 5 adjacent its connection with the tank 3, while the upper end of the pipe line 4 connects with the bottom of the tank 2.

In order to maintain a high water level within the tank 2, I provide a float actuated valve 8 that controls the inlet end of a pipe line 9 which extends into the tank 2, and it will be obvious that the valve 8 is open, except when a high water level is reached within the tank, as indicated by the float 10, and the pipe line 9 is in communication with a suitable source of water supply.

A pipe line 11 also extends between the tanks 2 and 3 and is connected to the tank 2 adjacent its bottom and to the tank 3 adjacent its top, the pipe line 11 acting to release steam from the tank 3 for a purpose which will be later described, and a pipe line 12 is likewise provided between the boiler and the tank 3, for passage of steam to the latter, it being noted that the pipe line 12 extends into the tank 3 and terminates in a vertical portion opening adjacent the top thereof. A valve 13 is mounted in the pipe line 11 and a similar valve 14 is mounted in the pipe line 12, the valves being actuated by levers 15 and 16 respectively that are secured to the stems thereof, and the levers are pivotally connected at their outer ends to a rod 17, whereby upon movement of the rod, the valves will be actuated in unison and in a manner so that when one valve is closed, the other will be open.

Mounted on suitable supporting means is an electric motor 18 that has secured to the outer end of its armature shaft 19 a worm 20 that meshes with a worm gear 21 which is fixed to a shaft 22, the latter being suitably mounted in bearings and has fixed thereto a crank element 23. A link 24 has its upper end pivotally connected to the rod 17 and its lower end to the crank element 23, with the result it will be seen that upon rotation of the gear 21, the valves 13

and 14 will be alternately opened and closed. Mounted midway its ends for limited movement on the shaft 22 is a tripping lever 25 of a length to extend upon diametrically opposite sides of the gear 21, and the lever is normally held in engagement with a pin 26 by a coil spring 27 that has one end connected to the lever and its opposite end to the gear.

Suitably secured to the top wall of the tank 3 is a bearing 28 having mounted for rocking movement therein, the upper bent end portion, 29 of a rod 30 that extends into the tank 3 and has a float 31 fixed to the inner end thereof. Fixed to the portion 29 of the rod 30 is one end of a link 32 that has its opposite end pivoted to the upper end of a vertical link 33, the latter having its lower end pivoted to the long arm 34 of a bell crank which has a roller 35 connected to the free end of the short arm 36 thereof, and the bell crank is pivotally mounted on a pin 37.

A substantially U-shaped member is mounted for rocking movement for disposal of the arms 38 thereof in the path of the roller 35. For that purpose, a bearing 39 is formed on the right portion of the U-shaped member, the bearing being mounted on a pin shaft 40 and the roller is disposed between the arms for engagement with either arm to rock the U-shaped member for a purpose which will be later apparent. Each arm 38 has loosely pivoted thereto, the lower apex end of a substantially triangular abutment lug 41, and the lugs are normally held by leaf springs 42 in the path of a pin 44 that is fixed to and extends laterally from an arcuate switch lever 43, midway its ends, as shown, the arcuate switch lever being pivoted at one end as at 45, and the opposite end is free, as well as is disposed in the path of the tripping lever 25. Secured to the switch lever 43 adjacent to its pivoted end is a mercury switch element 47 that is open when the lever 43 is in its upper position of Figure 1 and is closed when the lever is in its lower position of Figure 2. By that construction, it will be obvious that the float actuated bell crank acts to rock the U-shaped member for moving the pin 44 off the abutment lug 41 upon which it is mounted, for the switch lever to drop by gravity, to bring about closing of the switch and the tripping lever 25 will engage the free end of the switch lever and lift the same for disposing the pin upon one of the lugs 41 and thus open the switch.

In order to control the operation of the feeding mechanism solely by the quantity of water within the boiler, I provide a float actuated switch that includes a mercury element 48 fixed to the outer end of a rod 49 that is mounted for rocking movement in a cap 50 that closes a chamber having the float of the rod 49 disposed therein, as shown. The float chamber is provided by a housing 51 having nipples 52 formed on and extending in opposite directions therefrom, and the nipples are connected by elbows 53, to one end of the boiler, for disposing the rocking point of the rod 49 on the same level with that of the normal water level within the boiler, as shown by the dash line in Figure 1, so that the switch 48 will be open when the water level within the boiler is normal, but when the water level drops below normal the switch will close.

The switch 48 is in circuit with the switch 47 for opening and closing the circuit thereto, and the motor is also in the circuit, which likewise has a source of current 54 therein.

The operation is as follows:

Assuming that the parts of the apparatus are in the position of Figure 1, with the tank 3 being filled with water from the tank 2. When the tank 3 becomes filled, the float 31 will be at its uppermost position and the roller 35 will be moved from the position of Figure 1, it having moved the U-shaped member to the position of Figure 2 and caused the switch lever 43 to drop, as shown in that figure. In view of the fact that the valve 14 is closed at that time, the water cannot pass to the boiler, due to the steam pressure in the pipe line 5, and as the level of water in the boiler is normal, as shown in Figure 1, the switch 48 is open, therefore the apparatus is inactive.

However, when the water level in the boiler drops below normal, the switch 48 will close the circuit to the switch 47 and the motor will then be energized to move the valve 14 to open position, and the valve 13 to closed position. Steam from the boiler will then pass to the tank 3 through the pipe line 12, so that steam pressure in the tank and boiler will be equalized, to allow the water to flow by gravity from the tank 3 into the boiler. At the time the valves 13 and 14 reached their last mentioned position, the tripping lever 25 had engaged the switch lever 43 and lifted the latter to the position of Figure 3, and thereby had opened the circuit to the motor. When the water has been conducted from the tank 3 into the boiler, float 31 will have swung downward to its lowermost position, actuating the link and lever mechanism so that the roller 35 will have been swung through its arcuate movement to tilt the U-shaped member from its left hand, or that position shown at Figure 3, to the upright position illustrated at Figure 1. During such movement of the U-shaped member the pin 44 on the lever 43 will have dropped from the abutment 41 on the right hand arm of the U-shaped member with corresponding lowering of the lever 43 to effect closure of the mercury switch 47 and closure of the circuit to operate the motor 18 which then drives the worm wheel 21 through a half turn. This operation actuates the gear levers 15 and 16 to close valve 14 and open valve 13, cutting off steam supply from the boiler to tank 3 and causing the steam to pass from tank 3 to tank 2. During the last mentioned half turn movement of the worm gear 21 the tripping lever thereon will have engaged the free end of the switch lever 43 from its lowermost position to its uppermost position. During the interval when the switch lever was being elevated the water entering tank 3 from tank 2 will have elevated the float 31 and caused operation of the link and lever mechanism so that roller 35 returns to its left hand position as shown in Figure 2 and release of the switch lever 43 from its elevated position will bring the pin 44 to rest on the right hand abutment 41 of the U-shaped member as shown at Figure 3 so as to retain the motor circuit open until the water level in the boiler again drops to cause lowering of the float on the inner end of the rod 49 and closure of the mercury switch 48 to restart the motor and open steam line valve 14 while closing the upper steam line valve 13 with resultant shifting of the U-shaped member from the left hand position of Figure 3, the subsequent drop of the switch lever 43 with the further operation of the motor and repeating the cycle to effect proper filling of the boiler.

It is thought from the foregoing description

that the advantages and novel features of the invention will be readily apparent.

It is to be understood that changes may be made in the construction and in the combination and arrangement of the several parts, provided that such changes fall within the scope of the appended claims.

What I claim is:

1. An automatic feeding apparatus for a steam boiler, comprising a tank, a water pipe line between the tank and boiler, a valve controlled steam pipe line between the tank and boiler, a valve controlled steam outlet for the tank, motor operated means for actuating the valves to alternately introduce steam into the tank and to relieve steam therefrom, switch means in circuit with the motor, float actuated means for closing the switch means and controlled by water in the tank, means actuated by the motor for opening the switch means, and float actuated switch means controlled by water in the boiler and in circuit with the first switch means.

2. An automatic feeding apparatus for a steam boiler, comprising a water supply tank, a second tank elevated above the boiler and between the latter and the supply tank, check valve controlled pipe lines between the tanks and between the second tank and boiler, a valve controlled steam pipe line between the boiler and the second tank, a valve controlled steam pipe line between said tanks, motor operated means for actuating the valves of the steam pipe lines to alternately introduce steam into the second tank and to relieve steam therefrom, switch means in circuit with the motor, float actuated means for closing the switch means and controlled by water in the second tank, means actuated by the motor for opening the switch means, and float actuated switch means controlled by water in the boiler and in circuit with the first switch means.

3. An automatic feeding apparatus for a steam boiler, comprising the structure of claim 2, and said float actuated switch means including a

mercury element, a housing, opposed nipples formed on said housing and connected to the boiler, a rockably mounted rod extending through the housing and having the mercury element fixed to the outer end thereof, and a float on the inner end of said rod.

4. An automatic feeding apparatus for a steam boiler, comprising the structure of claim 2, and the first mentioned switch means including a lever pivoted at one end, a mercury element fixed adjacent said end, U-shaped means mounted for rocking movement, means on the U-shaped means for supporting the lever in a position with the switch means closed and in another position with the switch means open, and said lever being disposed in the path of said motor actuated means.

5. An automatic feeding apparatus for a steam boiler, comprising the structure of claim 2, and said float actuated means that is controlled by the water in the second tank including a rockably mounted rod extending into the second tank, a float on the inner end of said rod, a pivotally mounted bell crank linked to the rod, a lever included in the first mentioned switch means, means for supporting the lever in a position with the switch means closed and in another position with the switch means open, and said lever being disposed in the path of said motor actuated means.

6. An automatic feeding apparatus for a steam boiler, comprising the structure of claim 2, and said motor operated means including a worm fixed to the armature shaft of the motor, a gear having the worm meshing therewith, a shaft for the gear, a crank element fixed to the gear shaft and linked to said valves, a tripping lever associated with the gear shaft for rotation with the gear, and a lever included in the first mentioned switch means and arranged in the path of the tripping lever for actuating the switch means.

JAMES F. GILMORE.
